UNITED STATES PATENT OFFICE

150,012

DESIGN FOR A WIENER COOKER

Roy W. Hays, Rockford, Ill.

Application September 20, 1946, Serial No. 133,463

Term of patent 3½ years

(Cl. D81—10)

To all whom it may concern:

Be it known that I, Roy W. Hays, a citizen of the United States, residing at Rockford, in the county of Winnebago and State of Illinois, have invented a new, original, and ornamental Design for a Wiener Cooker, of which the following is a specification, reference being had to the accompanying drawing, forming a part thereof.

In the drawing:

Fig. 2 is a side elevational view thereof; and

Fig. 3 is a section taken along the line 3—3 of Fig. 1.

I claim:

The ornamental design for a wiener cooker, substantially as shown.

ROY W. HAYS.
